W. SMALL.

FASTENER FOR THE BOWS OF CAR TOPS,

APPLICATION FILED MAR. 27, 1917.

1,245,996.

Patented Nov. 6, 1917.

Inventor:
William Small
By Eric B. Murphy
Attorney

UNITED STATES PATENT OFFICE.

WILLIAM SMALL, OF MELBOURNE, VICTORIA, AUSTRALIA.

FASTENER FOR THE BOWS OF CAR-TOPS.

1,245,996.

Specification of Letters Patent.

Patented Nov. 6, 1917.

Application filed March 27, 1917. Serial No. 157,661.

To all whom it may concern:

Be it known that I, WILLIAM SMALL, a subject of the King of Great Britain and Ireland, and a resident of Albert Park, a 5 postal district of the city of South Melbourne, a suburb of the city of Melbourne, in the county of Bourke, State of Victoria, Commonwealth of Australia, (whose post-office address is 181 Beaconsfield Parade, 10 Albert Park, in the said city of Melbourne,) have invented a certain new and useful Improved Fastener for the Bows of Motor-Car Tops, of which the following is a specification.

15 This invention relates to motor car tops the bows of which when down at their rear ends rattle disagreeably, while passing over ruts or uneven roads. When strapped down the bows cannot always be tightened sufficiently to prevent the rattle, because the hole in the strap in advance of the tongue is frequently too far in advance for the tongue to enter, whereas the one behind it leaves the strap too slack.

20 25 The object of this invention is to provide a simple and effective fastening means for preventing the rattle and noise due to the bumping of the bows against each other. Provision is also made for preventing injury to the enamel or varnish on the bows.

Referring to the drawings,

Figure 1 is a side elevation of the lower member of the improved fastener, showing portion of a holding strap.

30 35 Fig. 2 is a section of the same the strap being omitted.

Fig. 3 is a plan of Fig. 1.

Fig. 4 is an end view of Fig. 2 looking in the direction of the arrow.

40 45 Fig. 5 is a side elevation of the upper member or bed of the fastener.

Fig. 6 is a section of Fig. 5. A layer of leather or other material is above the bed to protect the bow from injury.

50 55 Fig. 7 shows the upper and lower members separated by springs. The lower member in this instance has a flat bed.

Fig. 8 is an end view of Fig. 7.

55 60 Fig. 9 is an underneath view of the lower coil of one of the springs.

Fig. 10 is a side view of the same.

Fig. 11 represents the invention on a reduced scale as applied to a motor car body. The bows are tightly strapped together and cannot rattle.

65 70 This invention is applied to a motor car body 2 (see Fig. 11) from which protrudes an extension pin 3. The bows 4 which support the top are strapped together by a strap 5.

75 80 On reference to Fig. 1 it will be seen that a lower member is used having a pin hole 7 therein which passes over the extension pin 3 before referred to. The said lower member is secured to the extension pin by a locking screw 8. Through the said lower member is formed a lateral strap slot 9. The said lower member has a semicircular spring bed 11 the length of which depends upon conditions. Instead of the semi-circular spring bed 11 a flat spring bed 12 (see Figs. 7 and 8) may be used. Through the said spring bed are holes 13 to pass the lower ends of springs.

85 90 Resting upon the spring bed are two or more coiled springs. These are preferably conoidally wound having a small upper end 15 and a large lower end 16. The lower end has a centripetal extension 18 from which depends a vertical extension 19. The vertical extension of each spring passes through the adjacent hole 13 in the spring bed and is provided on its lower end with a head 20. The spring bed is thus secured between the centripetal extensions 18 and the heads 20 and the centripetal extensions will prevent the vertical extensions 19 being forced through the holes 13 when pressure is exerted upon the springs. The upper end of each spring has an eye 17. On account of the conoidal formation of the springs, their convolutions can be compressed within one another, thereby providing a movement of flexure of maximum extent; but if desired, cylindrical instead of conoidal springs may 95 be used.

95 100 Resting above the top of the springs is an upper member 24. The upper surface of this is preferably semi-circular in form or of other shape to accommodate the bows 4

and through it are holes 25 to pass bolts 21. These bolts have countersunk heads.

Resting upon the top face of the upper member may be a liner 26. This is of leather 5 or any other material and has countersunk holes in it to pass the heads of the bolts 21. The bolts pass through the eyes 17 at the upper ends of the springs and secure the upper member thereto by means of nuts 22 10 and washers 23.

With this invention when the lower bow of the top rests upon the upper member of the fastener, the free end of the strap is passed around the inside of all of the bows 15 and then brought down over the outside of the same. It is then passed through the buckle of the strap which strap has previously been passed through the lateral strap slot 9. When the free end of the 20 strap is pulled through the buckle and drawn it compresses the bows upon the upper member and the springs. These latter are compressed. The said strap can be so pulled that the tongue enters a hole in the 25 free end of the strap in such a manner that the bows are not overstrained to the upper member 24, nor are they understrained but are sufficiently tightly secured to prevent the rattle and noise sometimes associated 30 with similar connections.

Having now described my invention what I claim as new and desire to secure by Letters Patent is:—

1. An improved fastener for the bows of vehicle tops consisting in the combination 35 of a lower member adapted to be secured to the vehicle body, a semi-circular upper member to receive the lower bow of the top, conoidal springs disposed between said upper and lower members and a holding strap passing through said lower member and around the upper member and the bows.

2. An improved fastener for the bows of vehicle tops, comprising a lower member 45 adapted to be secured to the vehicle body and comprising a spring bed, an upper member adapted to support the bows of the top, coiled springs disposed between said upper and lower members, each spring having at its lower end a centripetal extension attached to said spring bed, and an adjustable strap passing over the bows and beneath the spring bed.

3. An improved fastener for the bows of vehicle tops, comprising a lower member 55 adapted to be secured to the vehicle body, said lower member having a spring bed, an upper semi-circular member adapted to accommodate the bottom bow of the top, coiled springs disposed between said upper and lower members, each spring having at its lower end a centripetal extension and a vertical extension passing from said centripetal extension and through said spring

bed, the lower end of the vertical extension 65 being provided with a head which is located beneath said bed, bolts passing through countersunk holes in said upper member to secure the upper ends of the springs thereto, and a holding strap passing over the bows 70 and through a slot in the lower member.

4. An improved fastener for the bows of vehicle tops consisting in the combination of a lower member adapted to be secured to the vehicle body, said lower member having a spring bed beneath which is a slot, an upper member adapted to accommodate the lower bow of the top, a liner in said upper member, coiled springs disposed between said upper and lower members, and a strap 75 passing through the slot in the lower member and around the upper member and the bows, whereby the tightening of said strap presses the bows against the liner and toward the lower member.

5. An improved fastener for the bows of vehicle tops, consisting in the combination of a lower member adapted to be secured to the vehicle body, an upper member adapted to receive the lower bow of the top, a liner 90 within said upper member, conoidal springs disposed between said upper and lower members, each spring having at its upper end an eye and at its lower end a centripetal extension and a vertical extension passing from the centripetal extension through the lower member, said vertical extension having a head which is located beneath said lower member, countersunk bolts passing through the bottom of the upper member 100 and said eyes, and an adjustable strap passing around the bows and through the lower member.

6. An improved fastener for the bows of vehicle tops, consisting in the combination 105 of a lower member adapted to be secured to the vehicle body and comprising a spring bed, a semicircular upper member adapted to accommodate the lower bow of the top, a liner within said upper member, conoidal springs disposed between the upper and lower members, each spring having at its upper end an eye and at its lower end a centripetal extension which rests on the flat spring bed and a vertical extension passing from the 110 centripetal extension downwardly through said spring bed, the lower end of the vertical extension having a head which engages beneath said bed, bolts passing through countersunk holes in the liner and the bottom of the upper member, said bolts passing also through said eyes, a nut and washer engaging each bolt beneath said eyes, and an adjustable strap passing through the lower member and over the bows.

7. A fastener for vehicle top bows, comprising, in combination, a lower member adapted to be fastened to the vehicle body

and having a strap opening in the lower portion thereof; an upper member adapted to directly support the lowermost bow; supporting springs interposed between said upper and lower members and tending to force the former away from the latter; and a fastening strap passing through said open-

ing and over the bows so as to draw said bows and said upper member downward, toward said lower member against the action of said springs, thereby to enable fine adjustment of said strap. 10

In testimony whereof I affix my signature.
WILLIAM SMALL.
